Inventor

Benjamin C. Clement

UNITED STATES PATENT OFFICE.

BENJAMIN CURT CLEMENT, OF ELMWOOD, WISCONSIN.

MOP HOLDER.

Application filed March 27, 1926. Serial No. 97,845.

The sole purpose of this invention is to effectively lock and hold the lever tightly until the operator desires to release the lever to remove the mop. It will automatically lock the lever when the lever is fully depressed to the mop stick, and will be easily and quickly disengaged by a slight pressure to the side with the thumb.

In order that the invention may be clearly understood the same will be hereinafter fully described as illustrated in the accompanying drawing, and the novel features thereof will be distinctly pointed out in the appended claims.

Figure 1 is a front view of a spring lever mop holder constructed in accordance with my invention, without the mop attached, in a closed and locked position.

Figure 2 is a front view of the same with mop attached.

Figure 3 is a view of the invention, and is shown in Figure 1 and Figure 2 attached to the mop handle, and is represented by the numerals 11.

Referring to the drawing in Figure 1 the spring lock 11, is shown attached to mop handle to come in contact with lever 12, at 9, just below the shoulder of lever 12.

In Figure 2, with mop in place the lever 12, is drawn up toward mop head so that the spring lock 11, is engaged with lever 12 at 10, a certain distance farther back toward the end of lever 12, depending on the size of mop being used.

Referring to Figure 3, the numerals 1 to 35 2 represent the width of the device. From 2 to 3 the height of shoulder. From 4 to 5 the height of the locking space. From 5 to 6 the width of the locking space, at a slight angle downward. 7 represents the 40 thumb lever. 8 represents two holes for small dimension wood screws to attach the device to the mop handle. It is to be understood that the details of construction as to size from 1 to 2, and from 2 to 3, and 45 from 4 to 5, and from 5 to 6, and the length of thumb lever (7), may be varied within the scope of the claims for best results.

Having fully described my invention, what I claim is:

1. A lock for mop holder levers comprising a split ring clip of flattened spring material adapted to embrace the handle of a mop, the free ends of the clip being curved outwardly and divergently to provide spring 55 guides for the lever.

2. A lock for mop holder levers comprising a split ring clip of flattened spring material adapted to embrace the handle of a mop, the free ends of the clip being curved outwardly and divergently to provide spring 60 guides for the lever, said clip adjacent said guides being provided with shoulders to receive edges of the mop lever.

In testimony whereof I affix my signature.

BENJAMIN C. CLEMENT.
